Primary Examiner — Charles D Hanson(74) *Attorney, Agent, or Firm* — Winston & Strawn LLP**CLAIM**

The ornamental design for an implant with internal porous surface structure, as shown and described.

DESCRIPTION

FIG. 1 is a top perspective view of an implant with internal porous surface structure in accordance with the present invention;

FIG. 2 is a side view thereof;

FIG. 3 is a top view thereof;

FIG. 4 is a bottom view thereof;

FIG. 5 is an exploded view of the internal porous surface structure for the implant of FIG. 1; and,

FIG. 6 depicts a region 5 in the implant of FIG. 1 from which FIG. 5 is enlarged.
